CLAIM

The ornamental design for a nighthawk kite, as shown and described.

DESCRIPTION

FIG. 1. Is a perspective view of my nighthawk kite design;

FIG. 2. Is a top view thereof;

FIG. 3. Is a bottom view thereof;

FIG. 4. Is a front view thereof;

FIG. 5. Is a rear view thereof; and,

FIG. 6. Is a right side view thereof, the left side view being identical thereto.

The structures shown in broken lines are for illustrative purposes only and form no part of the claimed design.
